(57) **CLAIM**

The ornamental design for a light as shown and described.

DESCRIPTION

FIG. 1 is a front perspective view of a light;

FIG. 2 is a lower front perspective view of FIG. 1;

FIG. 3 is a side view of FIG. 1;

FIG. 4 is a front view of FIG. 1;

FIG. 5 is a bottom plan view of FIG. 1;

FIG. 6 is a top plan view of FIG. 1;

FIG. 7 is an opposite side view of FIG. 3;

FIG. 8 is a rear view of FIG. 1; and,

FIG. 9 is a cross-sectional view taken in the direction of line 9-9 of FIG. 7.

The evenly-spaced broken line portion of FIGS. 1 through 9 is included to show environment that forms no part of the claimed design. In FIG. 7, dash-dot-dot-dash broken line represents a sectional designation that forms no part thereof.

1 Claim, 4 Drawing Sheets
